Martin Nystrom and
Joseph Spring
By: Wm. Best Atty.

UNITED STATES PATENT OFFICE.

MARTIN NYSTROM AND JOSEPH SPRING, OF CHICAGO, ILLINOIS, ASSIGNEES TO THE BRUNSWICK-BALKE-COLLENDER COMPANY, OF CHICAGO, ILLINOIS, A CORPORATION OF DELAWARE.

SPEED REGULATOR FOR PHONOGRAHS.

Application filed September 30, 1921. Serial No. 504,450.

To all whom it may concern:

Be it known that we, MARTIN NYSTROM and JOSEPH SPRING, citizens of the United States, residing at Chicago, in the county of Cook and State of Illinois, have invented certain new and useful Improvements in Speed Regulators for Phonographs, of which the following is a specification.

This invention relates to motors for phonographs and has for its principal object to provide a structure in which the adjustment for controlling the speed of the motor can be accomplished with a minimum of time and effort.

Another object of the invention is to produce a device for controlling the speed of the motor which can be adjusted without removing the motor from its support.

Another object of the invention is to place the means for adjusting the speed regulating device within the control of means above the motor board.

Other objects will become apparent as the description is read in connection with the accompanying drawing wherein the selected embodiment of the invention is illustrated and in which—

Fig. 1 is a side elevation of the device with certain details shown in section;

Fig. 2 is an inverted plan view showing parts of the speed regulating means; and

Fig. 3 is a detail in perspective.

Referring to the reference numerals, 10 indicates a top plate adapted to be secured 35 to the motor board and carry the motor frame 11 secured thereto by bolts 12 or in any other suitable manner. The presence of such a top plate is not essential to my invention and is illustrated principally to 40 indicate the top covering below which the speed controlling devices are usually located and which has made it necessary heretofore to remove the motor in order to adjust the speed regulator. It will be understood that we do not wish to be limited to 45 this or any other specific structure described except as is made necessary by the prior art.

13 indicates a spindle adapted to carry the usual record table. This spindle is suitably journaled in bearings which hold it in an upright position and is equipped with a worm 14 meshing with a worm gear 15 on a shaft 16 carrying a pinion 17 meshing

with a gear 18 which is driven by springs, not shown. The spindle 13 is also equipped 55 with a worm gear 19 meshing with a worm 20 on a governor shaft 21 which is journaled in suitable bearings 22 carried by the frame. Loosely mounted on the governor shaft is a sleeve 23 having a collar 24 at 60 one end and carrying a drum 25 at its other end. The web of this drum is provided with suitable perforations for the springs 65, secured at one end to the collar 24 and at the opposite end to the collar 26 rigid 65 with the shaft 21. These springs are equipped with weights 27 which, upon rotation of the governor shaft, are thrown outwardly and cause the drum to move to the right in Fig. 1 and bear against a brake pad 70 28, when the speed of the motor reaches the desired constant.

The motor may be allowed a number of different speeds by adjusting this brake pad 75 28 at greater or less distances from the normal position of the drum 25, when the devices are at rest. To accomplish this we make use of the lever indicated generally at 29 pivoted on a screw 30 threaded into a socket on the main frame. We prefer to 80 make this lever out of a single piece of sheet metal, bent into the desired conformation. As seen in Fig. 2, we provide it with an arm 31 which we prefer to bend at 32 and 33 so as to locate a portion 34 parallel 85 to the section 35 and through which the screw 30 is passed thereby forming a very strong connection. Another arm 36 is bent laterally from the portion 35, then downwardly, then into a substantially circular 90 conformation 37, then lapped on itself at 38 where it is secured by a screw 39 thus forming an arm having a suitable circular boss for the reception of a screw 40 by which the brake pad 28 is adjustably 95 mounted. Another arm 41 of the lever is inclined as indicated in the drawing and provided with a bifurcated end 42, one fork of which is bent at right angles to the arm 41 and provided with a projection 43 adapted to run between the threads 44 of an adjusting screw 45 swivelled in a cylinder 46 secured to the top plate 10. The other fork is given a reverse bend 47 to locate its end 48 parallel to the arm 41 and spaced from 100 the fork 43 a suitable distance to permit the

end 48 to bear against the outer surface of the threads 44. In order to provide a long bearing on the threads this fork may be equipped with an extension 49, see Fig. 3.

5 The upper end of the screw 45 is equipped with a knob 50 or other suitable hand device by which this screw can be rotated and beneath the knob is an indicator 51 loosely pivoted on the screw 45, supported upon an 10 annular shoulder 54 on the screw and normally held against movement by the clamping screw 52 employed to adjustably clamp the indicator down upon the annular shoulder 54 on the screw. The indicator finger passes 15 over a suitable dial 53 or other surface on which a speed indicating design may be drawn.

Heretofore it has been necessary to place the motor on a block, set it in motion, connect a speedometer to the spindle 13 or the 20 table carried thereby, and then make some adjustment in the devices carrying the brake pad 28 so as to have the drum 25 contact with the pad when the proper speed was 25 reached. The motor was then placed in the cabinet and the top plate 10 secured to the motor board or some other suitable part by screws or bolts. This top plate being of 30 relatively thin material and somewhat flexible would almost invariably be slightly distorted in securing it in place in the cabinet. This distortion would result in the change of 35 the relative position of the lever 29 and the adjusting devices and consequently the drum 25 would not come in contact with the pad 28 at the same speed as before the top plate was distorted. These prior devices were not 40 provided with an adjustable indicator finger and therefore the motor would have to be removed and another adjustment made in an attempt to have the brake applied when 45 the indicator finger indicated the desired normal speed.

With our invention a motor assembled as 45 indicated in Fig. 1 of the drawing is placed in the cabinet and made fast in any suitable manner, the speedometer is connected with the table on the spindle 13 and the knob 50 is turned until the motor is giving the desired 50 normal speed. The screw 52 is then loosened and the indicating finger 51 is moved to register with the point on the dial indicating the normal speed desired and the screw 52 is again set down. It will thus be 55 seen that this construction enables any person to make the necessary adjustment accurately and quickly and without the use of any special tool.

The construction of the lever 29, as de-

scribed, makes it possible to manufacture 60 this part in its entirety by machinery from ordinary sheet metal and consequently results in a considerable saving.

We are aware that changes in the form and proportion of parts, and in the details of construction of our invention may be made without departing from the spirit or sacrificing any of the advantages thereof, and we reserve the right to make all such changes as fairly fall within the scope of the 70 following claims.

We claim:

1. In a phonograph, a motor, a brake, means for applying and releasing the brake including a lever, a rotatable shaft adapted to operate said lever, an indicator rotatably mounted on the shaft, a knob fixed to the shaft and above the indicator, and a set screw passing downwardly through said knob and engaging said indicator to secure 80 it in an adjusting position.

2. In a phonograph, the combination of a top plate, a motor below said top plate, means for controlling the speed of said motor arranged below said top plate, means for adjusting said speed controlling means including a vertical screw extending through and rotatable in the top plate, a knob on said screw above said top plate, an index rotatably mounted on said screw and above the top 90 plate, and a set screw extending through said knob parallel to the axis of said screw and locking said index in an adjusted position.

3. In a speed regulator, the combination of a screw, a lever including a flat bar arranged edgewise to the length of the screw, an arm on said lever bent to present an edge in engagement with the threads of the screws, and another arm presenting a flat 95 side to the threads opposite to the first arm. 100

4. In a speed regulator, the combination of a governor including a brake drum, a brake lever composed of a flat metal strip having one arm bent to form spaced bearings, a fulcrum on which said bearings are 105 mounted, a second arm on said brake lever carrying a pad adapted to engage said drum and adjustable screws for operating said lever, and a third arm on said lever arranged edgewise to the length of said screws and 110 having bifurcations for engagement therewith, one bifurcation being bent to present an edge to the threads and the other bifurcation being arranged to present a side to the threads opposite to the first bifurcation. 115
